UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

CONTROL APPARATUS.

Application filed March 30, 1922. Serial No. 548,076.

This invention relates to electric current control devices, and especially to a device for controlling the bombardment of the electrodes of vacuum tubes during the evacuation thereof.

In the exhaustion of vacuum tubes the gas occluded in the grid and anode electrodes is driven out by heat developed in said electrodes through the bombardment thereof by 10 electrons emitted from the cathode and driven against said electrode by the difference of potential between the cathode and the other electrodes. The gas thus liberated is removed from the tube by the exhaust equipment. It is necessary to control the rate of bombardment since if gas is liberated from the electrodes faster than the exhaust equipment can remove it, the electrons will ionize 15 the gas, thereby setting free positive ions which will bombard the cathode and cause injury thereto. The control of the bombardment has heretofore been accomplished through a variation of the potential between the electrodes by the manipulation of rheostats or switches by an operator.

An object of the invention is to automatically control the rate of bombardment whereby the exhaust operation will be carried on under the proper conditions without 20 attention from an operator.

Another object of the invention is to utilize changes in pressure within the vessels of the electron discharge devices to vary the bombarding current.

Another object of the invention is a 35 simple, economical and efficient apparatus for automatically controlling the evacuation of the vessels of electron discharge devices.

One type of device for accomplishing 40 these objects comprises an ionization manometer in communication with the vessel to be exhausted, the variations in current from ionization due to changes in pressure within the manometer tube being utilized to effect changes in the field between the cathode and other electrodes of the tube being exhausted. In another type of this device the grid and anode are maintained at different potentials and variations in the grid potential due to current from ionization are utilized to vary the field between the cathode and anode.

Other objects and features of this inven-

tion will be apparent from the following specification and accompanying drawing 55 wherein: Fig. 1 discloses one embodiment of the invention; Figs. 2 to 6 disclose modified forms of the embodiment of the invention shown in Fig. 1.

Referring now to Fig. 1, 10 is a header of 60 an evacuating apparatus in communication with which are vessels 11 to be evacuated. Also in communication with the header 10 is a bulb 12 of an ionization manometer, in which are contained a cathode 13, a grid 14 65 and a plate electrode 15. One terminal of the cathode 13 is connected to the negative pole of a source of direct current electrical energy 16, preferably a generator, through a resistance 17. The other terminal is connected with the positive pole of the source 16 through a resistance 18. The grid 14 is connected to the positive pole of the source 16 through the winding of a relay 19, the movable contact 20 of which is connected to 70 the negative lead of the cathode 13 and the stationary contact 21 of which is connected to the positive terminal of said cathode. An ammeter 22 is contained in the lead between the relay 19 and the source 16. The 80 plate 15 is connected to the negative pole of the source 16 through a resistance 23 and an ammeter 24. Since the grid is maintained positive relative to the filament, a space current is caused to flow between these 85 electrodes. The electrons of the space current ionize the gas in the vessel 12 and the positive ions flow to the plate 15 which is negative with respect to the other two electrodes. This causes a flow of current in the 90 plate circuit. The space current flowing from the cathode 13 to the grid 14 is maintained substantially constant by virtue of the short-circuiting of the cathode through the closing of the contacts 20 and 21 whenever the current in the grid lead through the relay 19 tends to exceed a predetermined 95 value and the opening of said contacts when the current returns to said value. Any change in pressure within the vessel causes 100 a variation in the ionization current through the plate lead which variation is indicated by the ammeter 24. This arrangement of the ionization manometer is disclosed in my Patent 1,465,394 issued August 21, 1923.

The plate electrode 15 of the ionization

manometer is electrically connected with the grid 27 of an amplifier 28. The cathode 29 of the amplifier has one of its terminals connected to the negative side of the source 16 and has its other terminal connected to the positive side of said source through a resistance 30. The anode 31 of the amplifier is connected with the positive pole of the source 16 through the winding of a relay 32, the 10 fixed contact 33 of said relay being connected to the lead from the relay to the source 16. The movable contact 34 of the relay 32 is connected to a brush 35 of a D. C. motor 36 through the winding of a relay 37. A conductor 38 leads from an intermediate point of a resistance 30 to the lead between the brush 35 and the relay 37. The other brush 39 of the motor 36 is connected to the movable contact 40 of the relay 37. Two stationary contacts 41 and 42 are provided, which are adapted to be engaged by the movable contact 40 in its two positions respectively. The movable contact 40 engages the contact 42 when the relay 37 is deenergized. 25 The contact 42 is connected to the negative side of the source 16 through a switch 44 and a resistance 45. The contact 41 is connected with the positive side of said source through a switch 46 and a resistance 47. Each of the 30 resistances 45 and 47 is of a value several times that of resistance 30. The field winding 48 of the motor 36 is connected with the poles of the source 16. This arrangement provides for the running of the motor 36 in either direction. The brush 35 is maintained at a potential approximately midway between the potentials of the poles of its source 16 due to its connection to the resistance 30. The brush 39 is rendered either more negative or more positive than brush 35 according to whether the contact 40 engages the contact 42 or the contact 41. Current can thus be made to flow through the armature of the motor in either direction by the proper arrangement of the contact 40.

The two circuits for the motor are as follows: When the contact 40 engages the contact 42, as shown in Fig. 1, beginning with the positive pole of the source 16, the circuit 50 extends through the lower half of resistance 30, conductor 38, brush 35, armature of motor 36, brush 39, contact 40, contact 42, switch 44, resistance 45, and to negative pole of source 16. When contact 40 engages contact 41, the circuit extends from the positive pole of 16 through cathode 29, upper part of resistance 30, conductor 38, brush 35, armature of motor 36, brush 39, contact 40, contact 41, switch 46, resistance 49 and to the negative pole of 16. The motor current is so small in comparison to the heating current for cathode 29 that the flow thereof through the cathode circuit does not affect the operation of the amplifier 28.

60 A screw threaded shaft 49 is driven by the

motor 36, and on it is provided a rider 50 having threads to engage with the threads on the shaft, whereby rotation of the shaft in opposite directions causes the rider to travel longitudinally in opposite directions along the shaft. Portions of the rider project beyond the shaft and are adapted to engage with the movable part of the switches 44 and 46 to open them, springs being provided normally to hold said switches closed. 70 These switches 44 and 46 are provided to stop rotation of the motor armature 36 and thus prevent injury to shaft 49 and rider 50, when the rider 50 is in either of its extreme end positions. The rider 50 carries a contactor 51, one portion of which is in contact with and slides along a bar 52, and another portion of which wipes along a resistance 53. The bar 52 is connected to the positive pole of a source of D. C. electrical energy 54, 80 preferably a generator, the negative pole of which is connected to the negative terminals of the cathodes 55 of the devices to be exhausted. The resistance 53 is connected with the grids and anodes 56 and 57 of said devices through the resistances 58. Heating current is supplied to the cathodes 55 from a source of alternating current 59.

The resistances 58 assure simultaneous bombardment in all of the devices 11 as they 90 compensate for any difference in the internal resistance of the devices and thereby prevent such a difference in resistance between the various devices as would allow substantially all the current to flow through the device having the lowest internal resistance. Thus, the starting of the discharge in one of the devices does not materially affect the potential drop across the devices and the discharge 100 will start in all the devices at approximately the same time.

The operation of this device is as follows: After a comparatively high vacuum has been obtained within the vessels 11 by the exhaust apparatus, heating current is supplied to the cathodes 55 from the source 59 and a difference of potential is established between the cathodes and grids 56 and anodes 57 from the source 54; the rider 50 is placed at approximately its extreme right-hand position, the contact 40 being in engagement with the contact 42 and the contacts 34 and 33 being out of engagement. At the same time, heating current is supplied to the cathodes 13 and 29 from the source 16, the plate 15 is rendered negative, and the grid 14 positive with respect to cathode 13. The plate 31 is positive, and the grid 27 slightly positive, with respect to cathode 29 because of the resistance 28.

110 The direction of current flow through the motor 36 is such that the screw 49 rotates in a direction to move the rider 50 to the left thereby decreasing the resistance 53 and increasing the field between the electrodes 55 120

and 56 and 57. The bombardment of the grids and anodes 56 and 57 by the electrons heats them and liberates therefrom the occluded gases. The liberation of these gases 5 causes an increase in pressure in these vessels and also in the bulb 12 of the ionization manometer. As a result of the increase of pressure in the bulb 12, there will be an increase in the ionization current flowing 10 through the plate lead. This will cause an increase in the potential drop across the resistance 23 and will therefore make the grid 27 more positive. The space current of the amplifier 28 is thereby increased to a sufficient value to energize the relay 32, thereby 15 closing the circuit through the relay 37, thus disengaging the contact 40 from the contact 42 and bringing it into engagement with the contact 41. The direction of flow of current 20 through the motor 36 is thereupon reversed and the motor is caused to rotate the shaft 49 in such a direction as to move the rider 50 to the right, thereby increasing the resistance in the plate circuits of the devices 25 11. The intensity of the field between the cathodes 55 and the grids and anodes 56 and 57 is thereby decreased and the heating effect diminished. The rate of liberation of occluded gases from the electrodes is thereby 30 reduced. This action continues until the pressure is reduced within the devices 11 and the bulb 12 to a point where the ionization current in the plate lead 15 drops below a predetermined value. The potential of 35 the grid 27 thereupon is diminished sufficiently so that the space current in the amplifier 28 is no longer strong enough to energize the relay 32, whereupon the contacts 33 and 34 are separated. The relay 37 40 is then deenergized, allowing the contact 40 to be separated from contact 41 and brought into its normal engagement with contact 42. The direction of current flow through the motor 36 is now the same as at the start 45 of the operation. The above cycle is repeated as the pressure changes due to the rate of liberation of the occluded gases until the gases have been sufficiently removed. The degree of pressure is determined by 50 reading the ammeter 24. The rate of liberation of the occluded gas is thus controlled, and the pressure within the vessels maintained at a value at which there is no danger of destructive bombardment of the cathodes 55 by the positive ions.

Although the relay 32 is shown as being included in the output circuit of amplifier 28, it is apparent that the amplifier might be dispensed with and the relay 32 be included in the output circuit of the manometer 12.

Referring now to Fig. 2, 60 is the device to be exhausted and 12 is the bulb of an ionization manometer. The arrangement of the ionization manometer is the same as

that in Fig. 1, except that the plate lead of the ionization manometer is connected to the negative terminal of the cathode 29 of an electric discharge device 28. The cathode 29 is supplied with heating current from a 70 battery 61. The grid 27 is connected to the lead between the resistance 23 and the negative pole of the source 16. The anode 31 is connected with the negative terminal of the cathode 55, said cathode being supplied with 75 heating current from battery 62. The grid 56 and anode 57 are connected with the positive pole of the direct current source 54 through the resistance 53; and the negative pole of said source is connected to the negative terminal of the cathode 29. Thus the bombardment current of the device 60 is the space current of the device 28. During the operation, an increase in pressure in the bulb 12 causes an increase in the ionization current, thereby increasing the potential drop 80 across the resistance 23. This causes the grid 27 to become more negative with respect to the cathode 29, thereby decreasing the space current in the device 28, which is the 85 current flowing from the cathode 55 to the other electrodes of the device 60. The rate of liberation of occluded gases is thereupon decreased until the ionization current is reduced and the grid 27 becomes less negative 90 with respect to the cathode 29 thereby allowing an increase of space current in the device 28.

In Fig. 3 the device 11 to be exhausted is in communication with the header 10 of the evacuating device. The cathode 55 is supplied with heating current by a battery 63, and its negative terminal is connected to the negative pole of the source 54. The grid and plate electrodes 56 and 57 are connected to the positive pole of the source 54 through the winding of a relay 64 and resistances 65 and 66. The movable contact 67 of the relay 64 is in series with the winding of the relay 68, battery 69 and stationary contact 70 of the relay 64. The movable contact 71 of the relay 68 is connected to the lead from the relay 64 to the resistance 65, and the stationary contact 72 of the relay 68 is connected to the lead between the resistances 65 and 66. Under normal conditions, the contact 67 is out of engagement with the contact 70, and the contact 71 is in engagement with the contact 72. As the pressure within the vessel 11 increases due to the liberation of occluded gases, the resistance within the tube decreases and the space current increases. The relay 64 is thereupon energized and brings the contact 67 into engagement with the contact 70, thereby closing the circuit through the relay 68. The relay 68, being energized, separates the contact 71 from the contact 72 and introduces the resistance 65 into the plate circuit. The space current is thereupon decreased, and the rate of libera- 120 125 130

tion of occluded gases is diminished until the current in the plate circuit is no longer strong enough to energize the relay 64, whereupon the contacts 67 and 70 separate. 5 The relay 68 is deenergized and contacts 71 and 72 move into engagement, thereby short-circuiting the resistance 65.

Although, in each of the modifications above described, the grid and anode are electrically connected and simultaneously bombarded, it is apparent that either of them may be separately bombarded.

In Fig. 4, 11 is the device to be exhausted and is in communication with the exhaust header 10. In communication with the header 10 is the bulb 12 of the ionization manometer, the arrangement of which is the same as that described in connection with Fig. 1, except that one terminal of the cathode 55 of the device 11 is electrically connected with the lead between the plate 15 of the ionization manometer and the resistance 23. The remaining terminal of the cathode 55 is connected to the negative pole 25 of the source 54, the positive pole of which is connected to the plate 57 through the resistance 58. Heating current is supplied to the cathode 55 from the generator 73. The grid 56 is connected to the lead between the resistance 23 and the source of energy 16. The operation of this arrangement is as follows: An increase in pressure in the manometer bulb 12 causes an increase of ionization current in the plate circuit, thereby increasing the potential drop across the resistance 23. The grid 56 of the device to be exhausted is therefore rendered more negative with respect to the cathode 55 and reduces the space current flowing from the cathode 55 to the anode 57. The heating of the anode is thus diminished, and the rate of liberation of gas decreased. When the pressure within the bulb 12 has been reduced by the evacuation apparatus, the ionization current in the plate circuit of the manometer 12, becomes smaller and the potential drop across the resistance 23 is reduced. The grid 56 thereupon assumes a potential less negative with respect to the cathode 55 and the space current increases.

Referring to Fig. 5, 11 is the device to be exhausted. The cathode 55 is supplied with heating current from the source 73. The anode 57 is connected with one terminal 55 of the cathode through a resistance 58 and a source of D. C. current 54. The grid 56 is connected to the plate circuit between the source 54 and the cathode 55 through the winding of the relay 76, the battery 77, resistance 78 and battery 79. Shunted around the battery 77 and the resistance 78 are the movable and stationary contacts 80 and 81, respectively, for the relay 76. The batteries 77 and 79 are so poled as to make the grid 56 negative with respect to the cathode 55.

The contacts 80 and 81 are normally in engagement, thereby shunting out the battery 77. As the pressure increases within the bulb 12, the current flowing in the grid circuit due to ionization energizes the relay 76, thereby separating the contact members 80 and 81. This action introduces into the plate circuit the additional voltage drop through the battery 77 and renders the grid more negative, thereby increasing the resistance to the space current in the device 11. As the space current decreases, the temperature of the plate 57 drops and the rate of liberation of occluded gas diminishes. The ionization current in the grid circuit therefore becomes smaller and the relay 76 is deenergized, thus allowing 80 and 81 to come into contact, thereby shunting out the battery 77.

In Fig. 6, the cathode 55 of the device to be exhausted is supplied with heating current from the battery 82. The negative terminal of the cathode is connected to the positive brush of a series dynamo 83, the negative brush of which is connected to the grid 56 through the field winding 84 of the dynamo. The anode 57 is connected with the positive pole of a source of electrical energy 54 through the resistance 58, and the negative pole of the source 54 is connected to the positive pole of the dynamo 83. When no current is passing through the grid circuit, the residual magnetism of the field poles of dynamo 83 produces a slight negative potential on the grid. As the pressure within the device 11 increases, a positive ionization current is caused to flow in the grid circuit, thus increasing the field strength and causing an increase in the potential drop across the terminals of the armature of the dynamo, thus rendering the grid more negative with respect to the cathode. The increase of the negative potential on the grid with respect to the cathode increases the resistance of the tube and cuts down the space current flow. The rate of bombardment of the anode 57 is thereby decreased and the rate of liberation of occluded gases diminished. This action continues until the ionization current in the grid circuit has diminished sufficiently to render the grid less negative with respect to the cathode. The space current then increases and the cycle of operations is repeated.

In each of the modifications disclosed in Figs. 4, 5 and 6, the grid electrode may be freed of its occluded gases by interchanging the connection of the grid and anode so as to make the grid act as the collector of positive ions or, if the anode surrounds the grid, heat radiated against the grid from the anode may bring the grid up to the proper temperature to drive off the occluded gases.

It is to be understood that various modi-

fications may be made in this device without in any way departing from the spirit of the invention set forth in the appended claims.

What is claimed is:

5. 1. In a device of the character described, an electric discharge device to be evacuated, said device comprising a vessel containing a plurality of electrodes, means to cause one of said electrodes to emit electrons, a source 70 of potential connected between said electron emitting electrode and another of said electrodes for establishing a space current therebetween, and means controlled by the pressure of the gas within the device for automatically varying the potential of said source.
2. In a device of the character described, an electric discharge device to be evacuated, said device comprising a vessel containing 75 a plurality of electrodes, means to cause one of said electrodes to emit electrons, means to establish a space current between said electron emitting electrode and another of said electrodes, an ionization manometer in communication with said vessel, and means controlled by variations in the intensity of the positive ionization current of said manometer for varying the intensity of the space current in said electric discharge device.
- 20 3. In a device of the character described, an electric discharge device to be evacuated, said device comprising a vessel containing a plurality of electrodes, means to cause one of said electrodes to emit electrons, means to establish a space current between said electron emitting electrode and another of said electrodes, an ionization manometer in communication with said vessel, and means controlled by variations in the intensity of the positive ionization current of said manometer for varying the intensity of the space current in said electric discharge device.
- 25 4. In a device of the character described, an electric discharge device to be evacuated, said device comprising a vessel containing a plurality of electrodes, means to cause one of said electrodes to emit electrons, means to establish a space current between said electron emitting electrode and another of said electrodes, an ionization manometer in communication with said vessel, and means controlled by variations in the intensity of the positive ionization current of said manometer for varying the intensity of the space current in said electric discharge device, said controlling means including means for amplifying said positive ionization current.
- 30 5. In a device of the character described, an electric discharge device to be evacuated, said device comprising a vessel containing a plurality of electrodes, means to cause one of said electrodes to emit electrons, means to establish a space current between said electron emitting electrode and another of said electrodes, an ionization manometer in communication with said vessel, and means controlled by variations in the intensity of the positive ionization current of said manometer for varying the intensity of the space current in said electric discharge device comprising a variable resistance, motor driven means for effecting a change in said resistance and means for operating said motor in opposite directions, said means being controlled by the pressure of the gas within the vessel.
- 35 6. In a device of the character described, an electric discharge device to be evacuated, said device comprising a vessel containing a plurality of electrodes, means to cause one of said electrodes to emit electrons, means to establish a space current between said electron emitting electrode and another of said electrodes, means for varying the space current of said electric discharge device comprising a variable resistance, motor driven means for effecting a change in said resistance and means for operating said motor in opposite directions, said means being controlled by the pressure of the gas within the vessel.
- 40 7. In a device of the character described, an electric discharge device to be evacuated, said device comprising a vessel containing a plurality of electrodes, means to cause one of said electrodes to emit electrons, means to establish a space current between said electron emitting electrode and another of said electrodes, means for varying the space current of said electric discharge device comprising a variable resistance, motor driven means for effecting a change in said resistance and means for operating said motor in opposite directions, said means being controlled by the pressure of the gas within the vessel.
- 45 8. In a device of the character described, an electric discharge device comprising a vessel containing a plurality of electrodes, means to cause one of said electrodes to emit electrons, means to establish space current between said electron emitting electrode and another of said electrodes, an ionization manometer in communication with said electric discharge device, means for varying the space current within said electric discharge device comprising a variable resistance, motor driven means for effecting a change in said resistance, an amplifier, means in the output circuit of said amplifier responsive to current variations for controlling the direction of rotation of said motor, and means for varying the space current of said amplifier in response to variations in the positive ionization current of said manometer.
- 50 9. In a device of the character described, an electric discharge device to be evacuated, said device comprising a vessel containing a plurality of electrodes, means to cause one

- of said electrodes to emit electrons, means to establish space current between said electron emitting electrode and another of said electrodes, an ionization manometer in communication with said vessel, and means responsive to changes in the positive ionization current of said manometer for varying the intensity of the space current in said electric discharge device.
10. In a device of the character described, an electric discharge device to be evacuated comprising a vessel containing a plurality of electrodes, means to cause one of said electrodes to emit electrons, means to establish a space current between said electron emitting electrode and another of said electrodes, an ionization manometer in communication with said device and means responsive to changes in the positive ionization current in said manometer for varying the space current in said electric discharge device, said means comprising an amplifier, means for rendering the potential of the grid of said amplifier responsive to variations in the positive ionization current of said manometer, means in the output circuit of said amplifier responsive to changes in the space current of said amplifier and means controlled by said current responsive means for varying the space current of said device to be evacuated.
11. In a device of the character described, an electric discharge device to be evacuated, said device comprising a vessel containing a plurality of electrodes, means to cause one of said electrodes to emit electrons, means for establishing a space current in said device, said means comprising a source of energy and a variable resistance, motor driven means for operating said variable resistance, means for determining the direction of operation of said motor, an ionization manometer in communication with said device, an amplifier, connections between said manometer and said amplifier whereby change in the positive ionization current of said manometer produces change of potential of the grid of said amplifier and means in the output circuit of said amplifier responsive to changes in the space current for controlling the operation of said means for determining the direction of rotation of said motor.
12. In a device of the character described, a plurality of electric discharge devices to be evacuated, each of said devices comprising a vessel containing a plurality of electrodes, means for causing one electrode of each device to emit electrons and means for establishing a space current between each of said electron emitting electrodes and another of the electrodes in the same vessel, said means comprising a source of electrical energy, parallel connections from one terminal thereof connected to said electron emitting electrodes and parallel connections from the other terminal thereof to the other electrodes, said last named connection comprising resistance units.
13. In a device of the character described, a plurality of electric discharge devices to be evacuated, each of said devices comprising a vessel containing electrodes, means to establish a space current between each set of electrodes, and means controlled by the gas pressure within said device to regulate the space currents thereof.
- In witness whereof, I hereunto subscribe my name this 24th day of March A. D., 1922.
- WILLIAM G. HOUSKEEPER.
